UNITED STATES PATENT OFFICE.

GEORGE BRADY, OF JACKSON, MICHIGAN, ASSIGNOR TO HENRY H. LAMPERT, OF CHICAGO, ILLINOIS.

REINFORCEMENT-SUPPORT FOR CONCRETE STRUCTURES.

1,256,103.

Specification of Letters Patent. Patented Feb. 12, 1918.

Application filed November 23, 1914. Serial No. 873,464.

To all whom it may concern:

Be it known that I, GEORGE BRADY, a citizen of the United States, and a resident of Jackson, in the county of Jackson and State 5 of Michigan, have invented a new and Improved Reinforcement-Support for Concrete Structures, of which the following is a specification.

This invention relates to means for supporting reinforcing bars at a predetermined 10 distance from the falsework or other temporary supports or from roadways, on which slabs or other structures of concrete are molded; and it consists in the details of construction illustrated in the accompanying drawing and particularly pointed out in the claims following the specification.

In the accompanying drawing Figure 1 is a plan of reinforcements for concrete structures properly positioned by means of the 20 improved supports forming the subject-matter of the present invention. Fig. 2 is a view of a blank from which the supports are formed. Fig. 3 is a perspective of one of 25 these supports.

Similar reference characters refer to like parts throughout the several views.

The bars that reinforce concrete slabs, roadways and other structures are most efficient when positioned at the proper distance 30 from the lower sides of the slabs and from the surfaces of partitions. Small pieces of bricks, terra cotta tiles and wood and lumps of hard concrete are often employed to support the reinforcing rods and bars above 35 the falsework on which floor, sidewalk or other slabs are to be molded, while small stakes driven into the road-bed are also used to support the reinforcing bars which are 40 to be molded in the concrete slabs which are to constitute highway pavements. While these devices often cause undesirable cavities in the slabs, and are therefore objectionable, perhaps a greater objection is that 45 they are seldom of uniform height, so that it is impossible to obtain the greatest efficiency of the reinforcing bars. By the use of saddles of even height, the tensile strength 50 of the reinforcing bars, when properly placed, can be taken advantage of to the fullest extent.

The supporting devices shown in the drawings consist of small saddles bent up from properly sheared strips or blanks of

sheet metal, each consisting of the body 1 55 from which are sheared the tongues 2 and 3, and which blanks are provided with holes 4 if desired. The intermediate portions of the blanks are bent to form concave seats 5 in which the reinforcing bars 6 may lie. 60 The tongues 2 and 3 may be bent down to firmly grip the bars 6 and the cross-rods 7, if cross-bars are used in addition to the reinforcing rods 6. The upright portions or 65 legs 8 and 9 of the saddles may be of any desired height so as to hold the bars 6 the proper distance above the lower face of the finished slab. A foot 10 at the lower end of the leg 9 serves to prevent the saddle from falling over sidewise and also prevents 70 the saddle from sinking too far when used to support reinforcing bars above sandy road-beds.

When it is desired to employ these saddles for supporting reinforcing rods, they 75 will be placed in parallel rows proper distances apart, after which the reinforcing bars 6 will be laid upon them. Workmen will then bend the tongues 2 and 3 down over the bars 6, or if transverse rods 7 are 80 used, will bend these tongues around both the bars 6 and 7, thus firmly securing the bars and rods together, and at the same time insuring the bars and rods being held the proper distance above the falsework or other 85 surface upon which these saddles rest.

In case that it is desired to armor wooden partitions, these saddles can be secured to the partitions by means of nails or tacks driven through the holes 4, after which the 90 bars and rods can be secured in position in the same manner as before described. If the bar 6 and rod 7 are to be employed to reinforce a self-supporting partition, the saddles can be secured to the mold for one side 95 of the partition, after which the bars and rods may be secured in position, whereupon the mold for the opposite side can be erected immediately, or in sections as the work of filling in the concrete progresses. After the 100 concrete has set, the molds can be removed, the nails or tacks originally supporting the saddles and the reinforcing rods pulling out of the mold as it is being removed. The projecting nails or tacks can then be cut off 105 and the whole surface plastered in the usual manner.

Because of the small amount of metal

required to form these saddles, their cost will be very small, and a great saving of time and money will be effected by their use.

The curvature of that portion of the blank 5 that forms the part 5 of the saddle and also of those portions which join the part 5 and the legs 8 and 9 may be changed to suit the various reinforcements to be supported. The 10 proportions of the different parts of the saddles and the weight of the material forming the same will depend upon the load to be carried and the distance the bars and rods are to be supported above the surfaces supporting these saddles.

15 I claim:

1. A supporting device for reinforcements for concrete structures comprising a strip of sheet metal having slits adjacent to and parallel to opposite side edges at opposite 20 ends so as to form tongues along said opposite side edges, said strip being bent so as to constitute a pair of legs connected by a transverse portion which form a seat for the reinforcements, said tongues being bent 25 upwardly at the lines of juncture between the legs and transverse portion.

2. A supporting device for reinforcements for concrete structures comprising a strip of sheet metal having slits adjacent to and 30 parallel to opposite side edges at opposite ends so as to form tongues along said opposite side edges, said strip being bent so as to constitute a pair of legs connected by a transverse portion which forms a seat for 35 the reinforcements, said tongues being bent upwardly at the lines of juncture between the legs and transverse portion, the end of one of the legs being bent laterally to form a foot.

40 3. A supporting device for reinforcements for concrete structures comprising a strip of sheet metal having slits adjacent to and parallel to opposite side edges at opposite 45 ends so as to form tongues along said opposite side edges, said strip being bent so as to constitute a pair of legs connected by a transverse portion which forms a seat for the reinforcements, said tongues being bent upwardly at the lines of juncture between 50 the legs and transverse portion, the end of one of the legs being bent laterally to form a foot, said foot having perforations so that it may be secured in place by means of nails.

55 4. A supporting device for reinforcements for concrete structures comprising a strip of sheet metal having tongues adjacent to opposite side edges at opposite ends, said strip

being bent so as to constitute a pair of legs connected by a transverse portion which 60 forms a seat for the reinforcements, said tongues being bent upwardly at the lines of juncture between the legs and transverse portion.

5. A supporting device for reinforcements 65 for concrete structures comprising a strip of sheet metal having tongues adjacent to opposite side edges at opposite ends, portions of said strip being bent so as to constitute a pair of legs connected by a transverse portion which forms a seat for the reinforcements, said tongues being bent upwardly at the lines of juncture between the legs and transverse portion and being of a substantial length whereby said tongues may be 70 bent to hold a single rod or two superposed rods arranged on said seat at an angle to each other.

6. A supporting clip for the purpose described comprising an integral strip slotted 80 and bent to form a seat portion with depending legs at the ends thereof adapted to maintain the seat at an elevation above a suitable support, and flexible fingers formed from the metal at opposite sides of the strip 85 contiguous to the seat and leg portions, said fingers being spaced to accommodate a bar laid on the longitudinal axis of the seat, said fingers also being spaced apart from the transverse axis of the seat to accommodate 90 a bar laid on said axis, and adapted to being bent about a bar extending transversely of the seat to retain the clip in position relative thereto.

7. A supporting clip for the purpose described comprising a strip of metal slotted and bent to form a seat portion with supporting legs at its ends and flexible fingers at opposite sides of the seat portion, said fingers being disposed to accommodate a bar 100 extending transversely of the seat and being also spaced apart transversely of the seat to accommodate a bar laid longitudinally of the seat, said fingers also being adapted to be bent to engage a bar at points spaced 105 apart transversely of the seat whereby to retain the clip in definite position relative thereto.

In testimony whereof I sign this specification in the presence of two subscribing 110 witnesses.

GEORGE BRADY.
